Charles R. Seale.

UNITED STATES PATENT OFFICE.

HERBERT E. FEAKES, OF PATERSON, NEW JERSEY.

DEVICE FOR TEACHING TYPE-WRITING.

1,008,591.

Specification of Letters Patent. Patented Nov. 14, 1911.

Application filed February 20, 1911. Serial No. 609,809.

To all whom it may concern:

Be it known that I, HERBERT E. FEAKES, a citizen of the United States, residing at Paterson, in the county of Passaic and State of New Jersey, have invented a certain new and useful Improvement in Devices for Teaching Type-Writing, of which the following is a specification.

The invention relates to apparatus used in conjunction with writing machines as aids in teaching the "touch" system of type-writing, and the object of the invention is to provide an adjustable frame in which the hands of the operator are properly separated 15 and guided and the keyboard concealed from view.

Another important object is to provide means whereby the apparatus is easily applied to the machine and presented for service therewith, and to provide the adjustability required in adapting the apparatus to any of the well-known forms of typewriting machines.

The invention consists in certain novel 25 features and details of construction and arrangement by which the above objects are attained, to be hereinafter described.

The accompanying drawings show the apparatus applied on a typewriter, indicated 30 in dotted lines.

Figure 1 is a plan or top view, Fig. 2 is a corresponding front elevation, and Fig. 3 is a side view.

Similar letters of reference indicate the 35 same parts in all the figures.

A are clamps each having two upwardly projecting spurs A¹ A¹ adapted to apply on the inner face of the typewriter base-frame on opposite sides of the machine, 40 and a stud A² bifurcated at the upper end. A screw A³ extending through the stud near its base is arranged to impinge against the outer face of the frame in opposition to the spurs and thus hold the clamp reliably to 45 the machine.

In the bifurcation of each stud is mounted a close-fitting standard B held by a screw A⁴ and free to swing thereon to permit it to be inclined upwardly and forwardly at the desired angle. The standards are secured in the required positions by turning the screws A⁴ to clamp the jaws of the bifurcations thereon. The upper ends of the standards are screw-threaded and each receives two 55 nuts B¹ B² located on either side of a split-yoke B³ in the body or loop of which is car-

ried an end of a rod C extending transversely of the machine above the keyboard, on which three split-clasps C¹ C¹ are mounted each carrying a finger D. The clasps are 60 arranged to slide upon the rod in spacing the fingers D, and to rotate thereon in placing the fingers in the desired vertical angular position above the keyboard. When thus located the fingers are held by turning the 65 screws D² and compressing the arms C² C² of the clasps upon the rod. The latter is raised or lowered by manipulating the nuts B¹ B² which when tightened hold the rod firmly against axial or rotary movement. 70 The fingers D are each of wire having a loop D¹ including its screw I², so that by loosening the latter the finger may be adjusted at any desired angle laterally above the keyboard. 75

On the overhanging ends of the rod are mounted arms F F adjusted and held by the set-screws F¹ F¹. Each extends angularly upward from the rod and is drilled transversely near the upper end to receive a short bar G held by a set-screw F² and carrying on the inner end a cross-wire G¹ having its free ends coiled as shown into short helices G². The function of the helices at each side of the machine is to receive between their coils a sheet or shield H of paper, cardboard, or the like, serving to hide the keyboard from the operator.

In using the device the fingers D are spaced angularly to divide the keyboard 90 into two areas as nearly equal as may be, along a diagonal line near the center of the board, and are inclined downwardly to lie a little above the keyboard and follow its inclination. The keys in the two areas are 95 to be operated by the right and left hand respectively, the fingers D serving as stops or guides to prevent striking the keys of one area with the hand reserved for the other area, and as the keyboard is wholly or partially hidden by the shield H, the operator is forced to manipulate the keys in each area by touch and the sense of location alone.

The apparatus is light and does not interfere in any way with the operation of the 105 machine, being attached thereto only by the clamps A A at the base of the typewriter-frame. It is adjustable in all directions within its limits and is designed to serve with any of the common types of writing 110 machines without change other than in adjustment, and it may be easily dismounted

for transportation or transference to another machine of the same or other make.

Modifications may be made in the forms and proportions without departing from the invention, and parts may be used without the whole.

The fingers D may be used with the shield H omitted, or the shield employed alone as the learner advances in proficiency.

10 I claim:—

1. In a device of the character described, in combination, clamps adapted to grasp the base-frame of a typewriting machine, a standard adjustably mounted in each of said clamps, yokes carried by said standards, a rod adjustably mounted in said yokes, and fingers carried by said rod and extending over the keyboard of the machine, all arranged to serve substantially as and for the 20 purposes set forth.

2. In a device of the character described, in combination, clamps adapted to grasp the base-frame of a typewriting machine, a standard adjustably mounted in each of said 25 clamps, yokes carried by said standards, a rod adjustably mounted in said yokes, fingers carried by said rod and extending over the keyboard of the machine, arms on said rod, and a shield carried by said arms above 30 said fingers, all arranged to serve substantially as and for the purposes set forth.

3. In an attachment for typewriters, in combination, two clamps adapted to grasp the base-frame of the typewriting machine 35 on opposite sides thereof, a bifurcated stud on each of said clamps, a screw-threaded standard on each of said clamps adjustably held in such bifurcations, a split-yoke and holding nuts therefor adjustably mounted 40 on each of said standards, a rod held adjustably in said yokes, adjustable clasps on said rod, and adjustable fingers carried by said

clasps and extending over the keyboard of the machine, all arranged substantially as and for the purposes set forth.

4. In an attachment for typewriters, in combination, two clamps adapted to grasp the base-frame of the typewriting machine 45 on opposite sides thereof, a bifurcated stud on each of said clamps, a screw-threaded standard on each of said clamps adjustably held in such bifurcations, a split-yoke and holding nuts therefor adjustably mounted 50 on each of said standards, a rod held in said yokes, arms adjustably mounted on said rod, a bar on each of said arms, and coiled wires carried by said bars and adapted to receive and hold a shield, all arranged substantially as and for the purposes set forth.

5. In an attachment for typewriters, in combination, two clamps adapted to grasp the base-frame of the typewriting machine 60 on opposite sides thereof, a bifurcated stud on each of said clamps, a screw-threaded standard on each of said clamps adjustably held in such bifurcations, a split-yoke and holding nuts therefor adjustably mounted 65 on each of said standards, a rod held in said yokes, adjustable clasps on said rod, adjustable fingers carried by said clasps and extending over the keyboard of the machine, arms adjustably mounted on said rod, a bar 70 in each of said arms, and coiled wires carried by said bars and adapted to receive and hold a shield above said fingers, all arranged 75 substantially as and for the purposes set forth.

In testimony that I claim the invention above set forth I affix my signature, in presence of two witnesses.

HERBERT E. FEAKES.
